United States Patent Office

Des. 229,716

Patented Dec. 25, 1973

229,716

REAR PROJECTION VIEWER

Carl S. Shirley, Alexandria, Va., assignor to General Educational Technology Corporation, Alexandria, Va.

Filed Nov. 6, 1972, Ser. No. 303,763

Term of patent 14 years

Int. Cl. D16—03

U.S. Cl. D61—1 N

FIG. 1 is a top, front and left side perspective view of a rear projection viewer showing my new design;

FIG. 2 is a bottom, front and right side perspective view thereof, the rear being plain and unornamented.

I claim:

The ornamental design for a rear projection viewer, as shown and described.
